IGNITION TIMER

Application filed November 28, 1930. Serial No. 498,342.

This invention relates to ignition apparatus for internal combustion engines, and more particularly to the engine speed responsive mechanism for controlling the relation between the ignition timer cam and engine part which drives it, whereby to vary the timing of the ignition impulse relative to the cycle of engine operation.

Speed responsive ignition timing mechanism generally comprises a plate carried by the ignition timer drive shaft, and carrying movable weight members which move away from the shaft with increasing speed due to increase in centrifugal force, and toward the shaft with decreasing speed, due to the action of springs which yieldingly resist outward motion of the weights. The weights cooperate with parts connected with the ignition timer cam which is mounted upon the ignition timer drive shaft but which may rotate relative to the drive shaft. The ignition timer cam cooperates with the rubbing block of a circuit breaker lever to move the lever so that an ignition timer contact carried thereby will be separated from a stationary timer contact. In structures of this kind a spring is always employed to urge the circuit breaker lever into contact closing position when the cam does not touch the rubbing block and to maintain the rubbing block in contact with the cam when engaged by the cam to separate the timer contacts.

It is one of the objects of the present invention to improve speed responsive ignition timing controlling mechanism in a manner such that the mechanism will be less affected by the retarding force which is intermittently applied to the timer cam each time the cam engages the rubbing block of the circuit breaker lever, and also so that the mechanism will be less affected by torsional vibrations transmitted from the engine shaft to the ignition timer drive shaft.

In the disclosed embodiment of the present invention this object is carried out by increasing the mass directly rotating with the ignition timing cam without, however materially increasing the total weight of all of the rotating mass of the ignition timer. I have found that instead of mounting the

weights and weight plate directly upon the timer drive shaft, the desired results can be secured by mounting the weight plate directly upon the ignition cam so that the polar inertia of the cam will be increased very substantially due to the fact that the cam now carries the weight plate and weights which had been formerly carried by the timer drive shaft in the conventional ignition timer. The greater the mass rotating with the timer cam, the less will be the retarding effect of the periodic engagement of the rubbing block with the cam.

Further objects and advantages of the present invention will be apparent from the following description, reference being had to the accompanying drawing, wherein a preferred embodiment of one form of the present invention is clearly shown.

In the drawing:

Fig. 1 is a vertical longitudinal sectional view of an ignition timer embodying the present invention.

Fig. 2 is a fragmentary sectional view of parts shown in Fig. 1 drawn to a large scale in order to show details of construction, and is taken on the line 2-2 of Fig. 3, along which also certain portions of the sectional view of Fig. 1 are taken.

Figs. 3 and 4 are sectional views taken respectively on the lines 3-3 and 4-4 of Fig. 1.

20 designates an ignition distributor housing comprising a timer cup 21 and a shank 22 providing a bearing for an ignition timer drive shaft 23. The shaft 23 provides an extension 24 of smaller diameter providing a journal for a timer cam 25 mounted thereon and free to rotate relative thereto. The cam 25 is drivingly connected with, and supports 26 an ignition distributor rotor 26 carrying a center contact 27 and a distributing segment 28. The center contact 27 cooperates with a central, stationary distributor contact 29; and the segment cooperates with distributor posts 30 arranged in a circular row. The contact 29 and the posts 30 are electrically connected with metal sockets 31 and 32 respectively adapted to receive terminal clips by which wires may be secured thereto.

The cam 25 cooperates with the rubbing block 33 of a circuit breaker lever 34 pivoted upon a stud 35 carried by a circuit breaker plate 36 mounted in the cup 21. A 5 leaf spring 37 urges the rubbing block 33 toward the cam 25 and serves to conduct the current to the circuit breaker lever 34 and a movable timer contact 38 carried thereby. When the cam 25 is out of engagement with 10 the rubbing block 33 the contact 38 is urged by the spring 37 into engagement with a stationary timer contact 39.

As shown more clearly in Fig. 2, the hub 40 of the cam 25 is attached to a weight supporting plate 41 carrying studs 42 providing pivots for weights 43 which rest upon washers 44, and ridges 45 provided by the weight plate 41. Each weight 43 has an arm 46 cooperating with a surface 47 of a block 20 48 which is located upon the reduced upper portions 49 of studs 50 which are attached to a plate 51 attached to the shoulder 52 provided by the shaft 23. As shown more clearly 25 in Fig. 2, the shoulder 52 provides a bearing for the lower end of the hub 40 of cam 25. The plate 48 provides a central hole through which the lower end of the hub 40 of the cam 25 extends. The upper end portion 49 of the studs 50 carry also a hold down 30 plate 53 having off set extensions 54 which project above the weights 43 and limit upward movement thereof with respect to the plate 41. Each pair of adjacent studs 42 and 50 are connected with the ends of a coiled 35 spring 60, which tends to urge a surface 47 of the plate 48 toward a lever 46 of a weight 43 thereby urging the weight 43 toward the drive shaft extension 24. The hold down plate 53 is pressed on spring posts 50. 40 Springs 60 should not touch the hold down plate. As viewed in Fig. 3, the springs 60 tend to urge the block 48 in a counter-clockwise direction relative to the plate 41 or rather the plate 41 in a clockwise direction 45 relative to the plate 48. Motion of the plate 41 in this direction is resisted due to the fact that the larger portion of each stud 50 engages one side of a hole 61 in the plate 41 as more clearly shown in Fig. 4. The holes 50 55 61 are of such size as to permit relative rotation between the plate 41 and the plate 48 to permit advancing the cam 25 relative to the timer drive shaft 23.

As the speed of the shaft 23 increases, 55 centrifugal force acting upon the weights 43 will overcome the resistance of the springs 60 causing these weights to rotate counterclockwise about their pivots 42 as viewed in Fig. 3, thereby causing the levers 46 to rock 60 along the surfaces 47 of the plate 48, thus causing the plate 41 to be rotated in a counterclockwise direction relative to the plate 48 and hence relative to the shaft 23 which supports the plate 48. In this way the cam 25 65 which is directly attached to the weight plate

41 is caused to be rotated in a counterclockwise direction relative to the shaft 23 in order to advance the timing of the ignition with increasing engine speed. As the speed of the shaft 23 decreases, the springs 60 overcome 70 centrifugal force acting upon the weights 43 to cause them to move toward the shaft extension 24 as viewed in Fig. 3 thereby causing the weight plate 41 to move in a clockwise direction relative to the drive shaft 23 whereby the ignition timing will be retarded as the speed decreases.

In the conventional ignition timer having speed responsive control of the relation between the timer drive shaft and the ignition timer cam, the weight plate and weights are mounted upon the timer drive shaft, the weight plate occupying the position of the plate 51 shown in Fig. 2. The plate corresponding to plate 48 shown in the drawing with which the lever arms of the weights cooperate, is mounted upon the hub of the timer cam in the conventional ignition timer. It is therefore apparent that in the present invention the mass rotating directly with the timer cam 25 has been materially increased by substituting for a plate attached to the hub of the timer cam and having about the weight of the plate 48 shown in the drawing, the combined mass of weight plate 41 and weights 43. This substitution of parts adds very materially to the polar inertia of the cam 25 in order that the automatic control of the ignition timing will be substantially less effected by torsional vibrations of the shaft 23 resulting from similar vibrations of the engine crank shaft, and will be substantially less affected by the retarding impulses to which the ignition cam 25 is intermittently subjected due to its intermittent contact with the circuit breaker lever rubbing block 33.

It will be apparent that these improvements in the construction of the speed responsive mechanism have been provided without materially increasing the total weight of rotating parts of the timer and without appreciably increasing the cost of manufacture. As has been explained the disclosed embodiment of the present invention is designed to control an ignition timer cam which rotates counterclockwise, as viewed in the plan view. It will, therefore, be noted that the weights 43 are rocked in a trailing direction with respect to their pivoting posts 42, which rotate counterclockwise. It has been found that this arrangement tends to make the weights more stable because of air resistance than in the case of the conventional ignition timer using a centrifugal advance in which the weights are in leading positions with respect to their pivot posts.

While the form of embodiment of the present invention as herein disclosed, constitutes a preferred form, it is to be understood that other forms might be adopted, all coming

within the scope of the claims which follow.

What is claimed is as follows:

1. An ignition timer for internal combustion engines comprising, in combination, a circuit interrupter and a rotary cam for operating the same, and having a tubular hub, a drive shaft having an end portion on which the cam hub is journalled, a weight plate attached to the hub, a lever plate attached to the drive shaft on the side of the weight plate remote from the cam, movable weights located upon the side of the weight plate nearest the cam, arms on the side of the weight plate nearest the cam and cooperating with the weights, and means extending through the weight plate for rotatively connecting the arms and lever plate, and springs restraining movement of the weights due to centrifugal force.
2. An ignition timer for internal combustion engines comprising in combination; a circuit interrupter and a rotary cam for operating the same; a drive shaft in alignment with said cam; and speed responsive means for connecting said cam and drive shaft for varying the angular relation between them, said means comprising a weight plate having spaced apertures concentric to the axis of said plate and carrying movable weights, said plate attached to said cam; a drive plate secured to said drive shaft and carrying studs extending through said apertures of said weight plate to support lever arms cooperating with said weights, said studs cooperating with said apertures permitting relative rotation between said weight plate and arms to advance the cam; and springs restraining movement of the weights due to centrifugal force.
- 40 In testimony whereof I hereto affix my signature.
